UNITED STATES PATENT OFFICE

2,177,620

LIQUEFIED GAS DISPENSING SYSTEM

Loyd J. White, San Antonio, Tex., assignor to
Southern Steel Company, a corporation of
Texas

Application October 10, 1938, Serial No. 234,253

6 Claims. (Cl. 62—1)

This invention relates to liquefied gas dispensing systems of the general type disclosed in Patents Reissue No. 20,624, No. 2,121,673 and No. 2,121,675, wherein liquefied petroleum gas is stored in an underground tank and the generated gas is delivered through dispensing appurtenances, including a pressure reducing regulator, to a service pipe. This invention provides an expansion chamber associated with the service pipe and the tank through which low pressure gas passes into the service pipe at its lowest point. The idea is to insure a supply of gas at substantially constant pressure and to prevent accumulation of condensate in the service pipe which will interfere with the free passage of the gas to the consuming appliances.

Other aims and advantages of the invention will appear in the specification, when considered in connection with the accompanying drawing, wherein:

Fig. 1 is a fragmentary vertical sectional view, partly in elevation of a system embodying the invention;

Fig. 2 is a sectional view taken on the line 2—2 of Fig. 1; and

Fig. 3 is a vertical sectional view taken at right angles to Fig. 1, and on the line 3—3 of Fig. 2.

Referring particularly to the drawing, the system there shown is of the same general type as that disclosed in Patent 2,121,675. It includes an underground storage tank 10 having a riser or standpipe 11 to which is connected a combination valved fitting 12 and from which gas is delivered through a pressure reducing regulator 13 having an outlet conduit 14 for delivering low pressure gas to a service pipe, as will hereinafter be explained. These dispensing appurtenances, having been fully described in the aforementioned patent, require no further explanation.

The upper end portion of the standpipe and the dispensing appurtenances connected thereto are shown as being housed within a cylindrical protecting casing 15 which is shown as extending slightly above the ground level and it has a removable cover 16 to afford access to the filling and vapor return valves and all the parts within the casing. The bottom portion of the casing is removably mounted on top of a cylindrical expansion chamber 17 having a top wall 18 presenting a marginal peripheral flange 19 to which brackets 20 in the casing are bolted. The expansion chamber has a bottom wall 21 above the tank and a skirt 22 below the bottom shaped to conform to the contour of the tank and preferably tack-welded thereto. This expansion cham-

ber surrounds the riser or standpipe 11 and is shown as having a cylindrical sleeve 23 slightly larger than the standpipe welded to the top and bottom walls of the chamber so that the chamber may be slipped over the standpipe after it is welded in place on the tank and before the fitting 12 is assembled.

The outlet conduit 14 from the pressure reducing regulator 13 is shown as being welded into the top of the expansion chamber and a service pipe 24 is connected at its lowest point to the chamber near the bottom so that any condensate formed in the service pipe will drain back into the bottom of the expansion chamber and will not clog the system or interrupt the gas service.

The expansion chamber is arranged well below the maximum frost line and will remain at substantially the same temperature as that of the tank and the standpipe because it is intimately associated with both of them. Therefore, the low pressure gas and any condensate which flows back into the expansion chamber will always remain at a constant temperature and the condensate will immediately be re-vaporized. Furthermore, the expansion chamber will hold an appreciable quantity of low pressure gas delivered from the pressure reducing regulator, thereby insuring a continuous supply of gas at a substantially constant pressure. That is to say, the gas delivered through the service pipe is not subject to pulsations in pressure which might interrupt the flow to the gas consuming appliances.

From the foregoing description, it will be seen that the improved system is very simple in its design and construction. It can be manufactured at a relatively low cost and is easy to install. The parts are not subject to damage in shipment. Such systems do not require any re-vaporizing heat exchangers for the service pipe when installed in ordinary climates.

Obviously, the present invention is not restricted to the particular embodiment thereof herein shown and described. Moreover, it is not indispensable that all the features of the invention be used conjointly, since they may be employed advantageously in various combinations and sub-combinations.

What is claimed is:

1. In a liquefied gas dispensing system, an underground storage tank; a standpipe connected to the tank; dispensing appurtenances including a pressure reducing regulator connected to the standpipe; an expansion chamber supported on the tank in heat exchanging relation with the

tank and said standpipe and connected to receive gas delivered through said regulator; and a service pipe connected to said expansion chamber.

2. In a liquefied gas dispensing system, an underground storage tank; a standpipe connected to the tank; dispensing appurtenances including a pressure reducing regulator connected to the standpipe; a sheet metal expansion chamber mounted on the tank around said standpipe and connected to receive gas delivered through said regulator; and a service pipe connected at its lowest point to said expansion chamber above the bottom of the chamber.

3. In a liquefied gas dispensing system, an underground storage tank; a standpipe connected to the tank; dispensing appurtenances including a pressure reducing regulator connected to the standpipe; a substantially cylindrical expansion chamber having a bottom skirt portion secured to the top of the tank and having a sleeve surrounding the standpipe and in heat exchanging relation therewith; a conduit connecting the expansion chamber to the outlet of the pressure reducing regulator; and a service pipe connected to the expansion chamber.

4. In a liquefied gas dispensing system, an underground storage tank; a standpipe connected to the tank; dispensing appurtenances including a pressure reducing regulator connected to the standpipe; a substantially cylindrical expansion chamber having a bottom skirt portion secured to the top of the tank and having a sleeve surrounding the standpipe; a conduit connecting the expansion chamber to the outlet of the pressure

reducing regulator; a protecting casing removably secured to and supported on the expansion chamber; and a service pipe connected at its lowest point to the bottom portion of the expansion chamber.

5. In a liquefied gas dispensing system, an underground storage tank; a standpipe connected to the tank; dispensing appurtenances including a pressure reducing regulator connected to the standpipe; a substantially cylindrical expansion chamber having a bottom skirt portion secured to the top of the tank and having a sleeve surrounding the standpipe; a conduit connecting the expansion chamber to the outlet of the pressure reducing regulator; a marginal flange on the top of said expansion chamber; a protecting casing bolted at its lower portion to said flange; and a service pipe connected at its lowest portion to the expansion chamber.

6. In a liquefied gas dispensing system of the character described, an underground storage tank; an upstanding gas dispensing conduit connected to the tank; dispensing appurtenances including a pressure reducing regulator connected to the standpipe; a metal expansion chamber supported on top of the tank in heat exchanging relation therewith and connected to receive gas delivered through said pressure reducing regulator; a protecting casing for said dispensing appurtenances supported on said expansion chamber; and a service pipe connected to said expansion chamber.
